UNITED STATES PATENT OFFICE

ELMER R. NEVEL, OF LOCK HAVEN, PENNSYLVANIA

HOT-AIR-FURNACE ATTACHMENT

Application filed December 29, 1928. Serial No. 329,087.

The present invention relates to improvements in hot air furnaces and has reference more particularly to attachments to the combustion chamber for increasing the radiating surface thereof.

One of the important objects of the present invention is to provide a hot air furnace attachment that includes a formation of copper fins around the exterior of the combustion chamber of the hot air furnace, said fins being disposed in close proximity with respect to each other to increase the efficiency of the radiating surface of said combustion chamber.

Another important object of the invention resides in the provision of a hot air furnace attachment wherein the copper fins may be cast or spot welded to the outer surface of the cast iron combustion chamber.

Still a further object resides in the provision of a hot air furnace attachment that includes a band that encircles the major portion of the combustion chamber, and is fixedly secured thereto, a series of radially disposed fins being operatively connected at their inner ends with the band in such a manner as to prevent casual disengagement of the fins from the band.

Another object resides in the provision of a hot air furnace attachment of the above mentioned character that will at all times be positive and efficient in carrying out the purposes for which it is designed, the same being further simple in construction, inexpensive, strong and durable and further well adapted to the purpose for which it is designed.

Other objects and advantages of the invention will become apparent from the following description when taken in connection with the accompanying drawings.

In the accompanying drawings wherein like numerals indicate corresponding parts throughout the several views:

Figure 1 is a side elevation of the conventional hot air furnace, the casing therefor being shown in sections illustrating the combustion chamber formed with my improved copper radiating fins.

Figure 2 is a fragmentary sectional view

through a portion of the combustion chamber of the hot air furnace, and one of the fins that extends radially therefrom.

Figure 3 is a sectional view taken approximately on the line 3—3 of Figure 2, looking 55 downwardly.

Figure 4 is an enlarged sectional view through the combustion chamber showing the band encircling said chamber and being secured thereto and illustrating the manner 60 in which the copper fins extend radially of said band.

Figure 5 is a sectional view taken approximately on the line 5—5 of Figure 4.

Figure 6 is a top plan view of one of the 65 fins showing the manner in which the same is locked at its inner end behind the band that encircles the combustion chamber, the band and said combustion chamber being shown in section.

Figure 7 is a detail perspective view of 70 one of the radiating fins showing the tongues before they are bent into locking engagement with the inner face of the band.

Figure 8 is a fragmentary perspective view 75 of the band showing the vertically spaced slots provided therein for receiving the bendable tongues of said fins.

Figure 9 is a view similar to Figure 6 showing a modification of the combustion chamber 80 wherein the outer surface thereof is formed with an annular channel to accommodate the band, and

Figure 10 is a sectional view taken approximately on the line 10—10 of Figure 9.

In the drawings with reference more particularly to Figures 1 to 3 inclusive, the numeral 1 designates the cast iron combustion chamber of a hot air furnace A, the casing extends around the furnace structure being 90 shown at 2. Extending circumferentially around the combustion chamber 1 and being formed integrally therewith are the heat radiating fins 3 that are formed of copper and each of these fins is preferably of rectangular formation, the outer ends of the radially disposed fins terminating in spaced relation with respect to the casing as clearly shown in Figure 1.

The fins 3 are spaced a slight distance apart 100

with respect to each other so as to increase the radiating surface of the combustion chamber. These fins may be cast or spot welded to the outer surface of the cast iron combustion chamber 1.

With reference now to Figures 4 to 8, inclusive, there is illustrated a copper band 4 that encircles the combustion chamber 1, the ends of this split band terminating adjacent the respective sides of the usual opening 5 formed in the front side of the fire box 5 of the hot air furnace A. The band 4 is bolted at spaced intervals to the combustion chamber 1, as shown at 6, and the inner face of the band is spaced with respect to the outer face of the combustion chamber.

This copper band is formed at spaced intervals with a series of vertically spaced slots 7 for receiving the bendable tongues 8 that are formed on the inner end of each rectangular shaped copper heat radiating fin 9, it being understood of course that the band 4 is of a width slightly greater than the height of the radiating fins 9 so as to permit the bolts 6 to pass through the upper and lower edge portions of the band as more clearly disclosed in Figure 5.

The free ends of the bendable tongues 8 after being disposed through the respective slots 7 are bent laterally in opposite directions for engagement with the inner face of the band 4 and the outer face of the combustion chamber 1 and this detail is clearly illustrated in Figure 6. In this manner the heat radiating fins 9 will be positively anchored in proper position on the outer face of the circumferentially extending band 4, and the outer end of the fins terminate in spaced relation with respect to the circular casing 2.

In Figures 9 and 10 of the drawings there is shown a modification wherein the outer face of the combustion chamber 1 is formed with a circumferentially extending channel 10 to accommodate the copper band 4 so that the outer face of the copper band will lie substantially flush with the outer contour of the combustion chamber. Otherwise the band is attached to the combustion chamber in the usual manner as referred to above, and the bendable tongues 8 when engaged with the channeled portion 10 and the inner face of the band 4.

It will thus be seen from the foregoing description, that I have provided an attachment for hot air furnaces that will increase the radiating surface of the combustion chamber, and my attachment is of such a nature as to permit the same to be installed on the combustion chamber either as an integral part thereof, or as a separate unit, and this without going to much expense.

While I have shown the preferred embodiment of my invention it is to be understood that minor changes in the size, shape and arrangement of parts may be resorted to with-

out departing from the spirit of the invention and the scope of the appended claims.

Having thus described the invention, what I claim as new and desire to secure by Letters Patent is:—

1. The combination with the combustion chamber of a hot air furnace, of a band encircling said combustion chamber and being spaced therefrom, said band being formed with a series of vertically spaced slots at spaced intervals, a series of vertical radiating fins arranged radially with respect to the combustion chamber, and bendable tongues formed on the inner end of each fin for disposition through the respective slots in the band, the free ends of the tongues being bent laterally for engagement with the inner face of the band, and the outer face of the combustion chamber.

2. The combination with the combustion chamber of a hot air furnace, of a band encircling said combustion chamber and being spaced therefrom, said band being formed with a series of vertically spaced slots at spaced intervals, a series of vertical radiating fins arranged radially with respect to the combustion chamber, bendable tongues formed in the inner end of each fin for disposition through the respective slots in the band, the free ends of the tongues being bent laterally for engagement with the inner face of the band and the outer face of the combustion chamber, said band being of a width greater than the height of the fins, and attaching bolts for the band extending through the upper and lower edge portions of the band and the combustion chamber.

In testimony whereof I affix my signature.

ELMER R. NEVEL.
